UNITED STATES PATENT OFFICE.

JOSEPH E. RELLER, OF INDIANAPOLIS, INDIANA.

FLOOR BRUSHER AND OILER.

1,135,616.

Specification of Letters Patent. Patented Apr. 13, 1915.

Application filed November 18, 1912. Serial No. 732,123.

To all whom it may concern:

Be it known that I, JOSEPH E. RELLER, a citizen of the United States, residing at Indianapolis, in the county of Marion and 5 State of Indiana, have invented a new and useful Floor Brusher and Oiler, of which the following is a specification, reference being had to the accompanying drawings, and to the letters and figures of reference marked 10 thereon.

This invention relates to hand operated apparatus for expeditiously cleaning and oiling floors with one operation, the invention having reference more particularly to 15 a frame in which a brush and also a reservoir and an oil spreader and rubber are mounted.

The object of the invention primarily is to provide an improved floor oiler and polisher of such construction as to be adapted to be reversed in order that the rubbing portions thereof shall be worn away evenly and enabled to operate in the most satisfactory manner, a further object being to 25 provide a combined brusher and oiler of such construction as to be adapted for use either for brushing or for oiling and polishing a floor.

A still further object is to provide an 30 implement of the above mentioned character that shall be so constructed as to be of few parts, of simple construction and which may be cheaply produced, and so as to provide either a brush or an oiling implement without 35 it being necessary to provide a separate operating and controlling handle for each implement.

With the above mentioned and other objects in view, the invention consists in a 40 combination implement comprising an operating handle provided with a brush and also a reservoir and an oil spreader, the invention comprising also an improved floor oiler and an improved brush frame detachably connected in a novel manner with the 45 floor oiler; and the invention consists further in the novel parts and in the combinations and arrangements of parts as herein-after particularly described and claimed.

50 Referring to the drawings, Figure 1 is a perspective view of the complete invention; Fig. 2, a perspective view, partially broken away, of the improved frame whereby a floor may be brushed or cleaned without oiling it; Fig. 3, a vertical central section of 55 the oil-reservoir and rubbing swab on the

line 3—3 in Fig. 6; Fig. 4, a section approximately on the line 4—4 in Fig. 1 with the brush in non-operative position and serving as a weight for holding down the floor 60 oiler; Fig. 5, a fragmentary section approximately on the line 5—5 in Fig. 3; Fig. 6, a top plan of the improved swab holder; Fig. 7, a fragmentary section on the line 7—7 in Fig. 3; Fig. 8, a fragmentary perspective 65 view of the improved oil-reservoir; and Fig. 9, a fragmentary detail section of the brush and its frame.

Similar reference characters in the different figures of the drawings indicate corresponding elements or features of construction herein referred to.

The improved reservoir comprises a metallic wall having two principal side portions 1 and 2 and two relatively narrow end 75 portions 3 and 4, and also a top 5 secured to the upper end of the wall and provided with a filling neck 6 having a removable cap 7 thereon, the under side of the top 5 having a reinforcing bar 8 secured thereto 80 and extending transversely from one to the other of the side portions 2 and 3 of the wall. A valve stem 9 is screw-threaded into the bar 8 and extends through the top 5, the inner end of the stem having a downwardly 85 facing valve 10 thereon, the outer end of the stem having a hand wheel 11 fixed thereon. The length of the valve stem 9 is such as to maintain the valve at a suitable distance 90 inward from the plane of the normal lower end of the wall corresponding to the upper side of a wooden bottom 12 which is secured by suitable means to the wall, the bottom being set in a suitable distance above the plane of the lower end of the wall. The 95 middle portion of the bottom has a vertical feed-port 13 that extends therethrough and a valve seat 14 at the upper end of the feed-port. The end portion 3 of the reservoir wall has two projecting studs 15 and 16 and the portion 4 has two similar studs 17 and 18, the studs preferably extending through the wall portions and into the bottom 12. The valve 10 when forced down onto its seat 14 closes the feed-port 13 and obviously the 100 feeding of the oil from the reservoir may be regulated by adjusting the valve so as to partially open the feed-port.

A novel form of swab, which is highly efficient in operation, is provided and includes a holder which is preferably composed of a suitable number of wooden sec-

tions 19, 20, 21, 22, 23, all of equal length and thickness, and a relatively thinner section 24, each section, excepting the thinner one, having a recess 25 in one side of its 5 lower portion formed by rabbetting the section before placing the sections together, the section 24 being placed against the section 23 so as to partially cover the recess in the section 23. It will be seen that the re- 10 cesses constitute grooves at the joints of the several sections into which the upper edges of a suitable number of sections 26, 27, 28, 29, 30, of the swab are inserted and secured preferably by small nails 31, the edge por- 15 tions of the sections being compressed in the grooves when the sections of the holder are forced together closely and secured as a unitary whole by means of a suitable num- 20 ber of rivets 32, 32' extending through all the sections. The sections of the swab prefer- 25 ably are composed of suitable felting, and a binder 33 of similar material is placed around the swab sections and extends up- 30 ward and is suitably tacked or otherwise se- 35 cured to the exterior of the holder, the binder extending entirely about the swab sections and the holder, and the upper portion thereof with the holder is inserted in the lower portion of the wall of the reser- 40 voir so that the holder is in contact with the bottom 12. The upper side or top of the holder has also two diverging branch channels 36 and 37 extending from one end of the chan- 45 nel 34, and two diverging branch-channels 38 and 39 extending from the opposite end of the main channel, there being preferably a suitable number of lateral channels 40 and 41 extending from opposite sides of the main 50 channel. Two feed holes 42 and 43 extend downward from the channels 36 and 37 re- 55 spectively, two feed holes 44 and 45 extending downward from the channels 38 and 39 respectively, other feed holes 46 and 47 ex- 60 tending downward from the ends of the lat- 65 eral channels, all the feed holes being ar- ranged to conduct the oil so as to deliver it between two adjacent swab sections, in order that the oil may freely work down to the floor without necessitating the saturation of the whole of the swab. The swab holder is provided with a suitable number of holes 48, 48' to receive screws 49, 49' which are in- 65 serted between adjacent swab sections and screwed into the bottom 12 whereby the swab is detachably secured to the bottom.

A suitable handle 50 is provided to which two outspreading arms 51 and 52 are secured, the arms being adapted to tightly 65 embrace the two end portions 3 and 4 re-

spectively of the reservoir wall and be in horizontal position when the reservoir is in normal upright position, the arms extending slightly beyond the plane of the normal front of the reservoir. The arm 51 has two 70 sockets 53 and 53' receiving the studs 16 and 15 respectively, the arm 52 having similar sockets 54 and 54' receiving the studs 18 and 17 respectively, whereby the arms are connected to the reservoir and may be dis- 75 connected therefrom by springing the arms apart from the studs. The arms 51 prefer- 80 ably has also two apertures 55 and 56 therein, the arm 52 having two apertures 55' and 56' therein at opposite sides or forward and 85 rearward of the reservoir, in order that a brush frame may be detachably connected to the reservoir frame.

A suitable brush frame comprises a main 90 bar 57 that is normally in horizontal position and from which extends two guide bars 58 and 59 at right angles thereto, two arms 60 and 61 extending from the two guide bars respectively and adapted to closely embrace the outer sides of the arms 51 and 52. The 95 ends of the arms 60 and 61 are provided with hinge pins or pivots 62 and 62' that are inserted through the apertures 56 and 56', respectively, and pivotally connect the brush frame to the oiler frame, a tubular 100 spreader bar 63 being inserted between the arms 51 and 52 and receiving the inner ends of the pivots for holding the arms 51 and 52 at the required distance apart when dis- 105 connected from the reservoir, but the bar 63 may be omitted when the arms are connected to the reservoir. The arms 60 and 61 are provided also with two locking pins 64 and 64' respectively that are inserted in the ap- 110 pertures 55 and 55' to prevent relative piv- 115 otal movement of the brush frame, and it will be understood that the arms 60 and 61 may be sprung apart to disconnect them from the arms 51 and 52. The bar 57 has two guideways 65 and 65' therein and the 120 guide bars 58 and 59 have vertically ar- 125 ranged slots or guideways 66 and 66' therein, respectively that are approximately at right angles to the arms 60 and 61 respectively.

A suitable brush comprises a back 67 of suitable length to fit slidingly between the guide bars 58 and 59, and bristles 68 or the like secured to the back. The ends of the back 67 are provided with guide pins 69 and 69' that extend through the guideways 66 and 66', and the back is provided also with two upwardly extending guide pins 70 and 70' that extend through the guideways 65 and 65' respectively for holding the brush 125 in proper upright position, two coil springs 71 and 71' being inserted between the bar 57 and the back 67 and retained by the up- 130 right guide pins which may consist of screws having heads to serve as stops, the brush

being stopped also when forced downward by the springs relative to the frame when the guide pins 69 and 69' arrive at the lower ends of their guide ways.

- 5 In practical use, oil required for the floor is regulated by the valve 10 and the flow entirely stopped by the valve when the apparatus is not in use. The implement is placed on the floor somewhat as illustrated 10 in Fig. 1 and pushed ahead of the operator and obviously may be lifted from the floor and drawn backward and then lowered to the floor again, so that the floor may be thoroughly brushed or swept in order to remove dust in advance of the application of 15 the oil, in order that the floor may be left in clean and polished condition. If it is preferred, however, to first cleanse the floor by other means the brush may be swung up 20 on to the handle while oiling the floor if considerable weight is desired, or may be entirely detached by springing the arms 60 and 61 apart until the pivots 62 and 62' are disconnected from the arms 51 and 52. If it is 25 desired to brush the floor and not oil it, it will be understood that the swab holder may be detached from the bottom 12 and the weight of the reservoir and oil therein will 30 serve to hold down the brush, or the swab 35 may remain connected to the reservoir and the brushing be accomplished by simply elevating the handle 50 somewhat and preventing the oil from feeding down to the floor through the swab. In case it is not desired 40 to have the brush weighted it is evident that after disconnecting the brush frame from the arms 51 and 52 the latter may be disconnected from the reservoir, after which the arms 60 and 61 may be connected to the arms 45 51 and 52 as illustrated in Fig. 2, and brushing operations may be easily accomplished.

It will be understood from the foregoing 45 that the reservoir may be reversed in arrangement relative to its frame and also that the swab may be discarded when worn out, together with its holder, and a new one applied in its place, the incidental expense being relatively small. Also it is evident that 50 a new brush may be readily substituted for a worn out brush at small expense.

Having thus described the invention, what is claimed as new is:—

1. A floor oiler including means for feeding and spreading oil provided with an operating-handle, and means detachably connected substantially with the handle for carrying a weight in advance of the feeding and spreading means.

2. A floor oiler including a main frame, an oil-reservoir secured to the frame, a swab secured to the oil-reservoir, a frame detachably secured to the main frame and a weighting device mounted in the latter frame.

3. A floor oiler including a main frame and an operating handle thereon, an oil-

reservoir secured to the frame, a swab secured to the reservoir and adapted to retain and gradually feed oil from the reservoir, a weight frame pivotally connected to the main frame to be moved to or from the handle and having a weighting device thereon, and means for fixedly securing the weight frame to the main frame when moved from the handle.

4. A floor oiler including a reservoir having a bottom provided with a feed-port, a swab holder secured to the bottom and oil-retaining swab sections secured thereto, the holder having also feed-channels in the top thereof connected with the feed-port and also feed-holes extending therethrough from the feed-channels in planes between the swab sections.

5. A floor oiler including a swab holder having a feed-channel in the normal upper side and grooves in the under side thereof, the holder having also feed-holes extending therethrough from the feed-channel on either side of the grooves, swab sections compressed and secured in the grooves, and a binder extending about the swab sections and secured to the swab holder.

6. A floor oiler including a closed reservoir having a bottom provided in the middle portion with a feed-port, a swab holder removably secured to the bottom and having grooves in the under side thereof, the top of the holder having a channel therein extending under and also away from the feed-port, the holder having holes extending therethrough from the channel, oil-retaining swab sections secured in the grooves to the holder, and a valve stem screwed into the top of the reservoir and having a valve thereon adjacent the upper end of the feed-port.

7. The combination of a reservoir having two studs on each of two opposite ends thereof, a swab connected to the reservoir, a handle, and two frame arms secured to the handle and embracing the ends of the reservoir, each arm having two sockets therein receiving two of the studs, each arm having also two apertures therein whereby to connect a weighting device to the frame.

8. In a floor oiler, the combination of a reservoir having a bottom and also having two studs on one end and two studs on the opposite end thereof, the studs extending into said bottom, a handle having two arms embracing the said two ends respectively, each one of the arms having two sockets therein receiving the two studs of the end, said arms being adapted to be sprung away from said ends to release said studs from said sockets, a swab holder secured to said bottom, and an oil-distributing swab secured to the holder.

9. In a floor oiler, a reservoir comprising two principal side wall portions and two

relatively short end wall portions, a top secured to the top of the wall portions and having a reinforcing bar secured to the under side thereof, the bar extending from one to the other of the principal side wall portions, a valve stem screw-threaded into said bar and extending through said top, a hand-wheel secured to the outer end of said stem, a valve on the inner end of said stem, 10 and a bottom set in above the plane of the lower end of said wall portions and secured to said portions, said bottom having a feed-port therein and a valve seat at the upper end of the feed-port adjacent to said valve, 15 in combination with a swab holder secured to said bottom and embraced by the lower end portions of said wall portions, and an oil-retaining and spreading swab secured to said holder.

20 10. In a floor oiler, the combination with a reservoir having a bottom provided with a feed-port, of a swab holder composed of a plurality of wooden sections that are respectively equal in thickness and also a relatively thinner section, all the sections being secured together, each section excepting the thinner one having a recess in the lower portion of one side thereof, said thinner section being arranged on an outer one of the recessed sections and partially covering the recess therein, a plurality of screws extending through said holder on either side of said recesses and into said bottom to removably secure the holder to the bottom, the

upper side of said holder having a feed-channel therein extending under said feed-port, and a plurality of swab sections compressed in said recesses and secured to said holder sections respectively, one of said swab sections being engaged and composed 40 in the adjacent recess by said thinner one of the holder sections.

11. In a floor oiler, the combination with a reservoir comprising a wall portion and a bottom secured to the wall portion and having a feed-port in the middle portion thereof, of a swab holder secured to the bottom and having a main feed-channel in the upper side thereof extending under the feed-port, the upper side of the swab holder having 50 also branch channels extending divergently from opposite ends respectively of the main feed-channel and other branch channels extending laterally from opposite sides respectively of the main feed-channel, the under side of said holder having grooves therein, said holder having feed-holes extending therethrough from the main feed-channel and the ends of the branch channels respectively on either side of the grooves, 55 and swab sections compressed and secured in the grooves.

In testimony whereof, I affix my signature in presence of two witnesses.

JOSEPH E. RELLER.
